TOY REINDEER

Thomas Dam, Gol, Denmark

Filed Mar. 12, 1962, Ser. No. 69,228

Term of patent 3½ years

(Cl. D34—2)

I claim:

The ornamental design for a toy reindeer, as shown.
